Attorneys

UNITED STATES PATENT OFFICE

EDWARD SCHULTZ, OF CHICAGO, ILLINOIS

ASH RECEPTACLE

Application filed July 30, 1928. Serial No. 296,264.

The principal object of this invention is to provide an ash receptacle and stand for tobacco smokers that is economical in manufacture, durable in use and refined in appearance.

A further object of this invention is to provide an ash receptacle and stand for tobacco users that is of considerable capacity and holds the undesired ashes and cigar and cigarette butts out of sight.

A still further object of this invention is to provide an ash and cigar and cigarette butt receptacle that prevents the odor and smoke from the discarded butts from escaping from the same.

A still further object of this invention is to provide an ash receptacle for receiving ashes and the like from cigars and cigarettes that is readily and easily emptied.

A still further object of this invention is to provide an ash receptacle and stand for tobacco smokers that is easily assembled or dismantled for packing or shipping.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a perspective view of my complete device ready for use with a section cut away to more fully illustrate its construction.

Fig. 2 is a side sectional view of the lower portion of the receptacle cover member and more fully illustrates the construction of the trap door mechanism.

Fig. 3 is a cross sectional view of the trap door retrieving means and is taken on line 3-3 of Fig. 2.

Fig. 4 is a side view of the receptacle portion and the upper portion of the stand.

Fig. 5 is a side sectional view of the lower portion of the cover member and shows the trap door in an open position for allowing waste material to fall into the receptacle.

The objections to the smoking stands now on the market are their great bulk, their dif-

ficult emptying features, and their inability to retain the odor and smoke from cigarette and cigar butts thrown therein. I have overcome all these disadvantages as will be appreciated by those skilled in the art.

I have used the numeral 10 to designate the stem of the stand portion of the device. Secured to each end of this stem by suitable means is a disk or plate member which I have designated by the numerals 11 and 12 respectively. Secured by stove bolts 13 to the plate 11 are the three feet members 14, designed to rest on the floor or other surface and support the complete device. Secured by rivets or the like to the upper plate 12 are the three bracket members 15 each having a flat vertical portion 16 in their length as shown in Fig. 1 and Fig. 4. The free ends of the feet and bracket members may extend into any suitable graceful curve, thereby not only making the device artistic and pleasing to the eye, but preventing the ends from catching onto clothing and the like.

Loosely resting on the plate member 12 and adjacent the flat portions 16 of the brackets 15 is my cup-shaped receptacle 17. I have used the numeral 18 to designate the cover member of the receptacle which is supported on the upper marginal edge of the receptacle by having its marginal edge bent around the upper marginal edge of the receptacle as shown in Fig. 1. By this construction the receptacle and its cover member may be lifted upwardly from the plate 12 and brackets 15 for the emptying of the receptacle, or when the receptacle portion is desired to be set on the table or the like. The cover member is easily removed from the receptacle portion by lifting upwardly. The numeral 19 designates an opening in the center of the cover member to which the cover member extends inwardly and downwardly into the receptacle as shown in Fig. 1. By this construction the ashes or cigar butts easily slide downwardly on the cover member, through the opening 19 and into the receptacle. Secured by suitable means to the under side of the cover member is a biforked bracket member 20. Extending through the two extensions of this bracket member is a small pin or shaft 21. The

numeral 22 designates a trap door hinged on the small shaft 21 by having the same pass through two ears 23 integrally formed on the trap door, as illustrated in Fig. 2, and so positioned that when the trap door is swung in one direction the opening 19 will be closed thereby. The numeral 24 designates a coil spring around the shaft 21 having one of its ends engaging the bracket 20 and its other end engaging the back portion of the trap door 22. By this arrangement the trap door will be yieldingly held in a closed position as shown in Fig. 2 by the coil spring 24. Extending vertically through the cover member 15 and in a plane between the two extensions of the bracket member 20 is the bearing member 25. Journalized in this bearing member and having its lower end engaging the trap door is the push rod 26. Secured to the top of the push rod is an enlarged head 27. By this construction, when force is exerted downwardly on the head member the push rod 26 will be forced downwardly and in turn will force the trap door 20 to an open position as shown by the dotted lines in Fig. 2, thereby allowing any ashes, cigarettes, or cigar butts that may be resting on the trap door to pass into the receptacle. When pressure is relieved from the head 27, 30 the coil spring 24 will return the trap door to a closed position, which will raise the push rod upwardly in its bearing member. When the trap door is in a closed position it will be impossible for any odor or smoke 35 from the unextinguished cigarette or cigar butts to pass from the receptacle. I have used the numeral 28 to designate the two curved horizontal plate members designed to hold a lighted cigarette or cigar while not being used by the smoker. The ignited end of the cigarette or cigar should extend toward the center of the device, thereby allowing any ashes that might fall from the same to deposit on the trap door. 40 The numeral 29 designates a tongue integrally formed in the trap door and so located that when the push rod 26 is forced downwardly its lower end will be engaging in the same as shown in Fig. 5. This arrangement 45 not only causes the trap door to open its maximum capacity with a minimum movement of the push rod but when the trap door automatically closes it will have more direct upward pressure on the push rod. 50 When the device is to be assembled for packing or shipping the feet 14 should be removed and a plate member 11, which is secured to the stem 10, is placed outside the receptacle. The cover member may be placed 60 between the three bracket members 15, and the feet may be placed along the stem 10, thereby making the complete device very compact and capable of being placed in a 65 very small package or container.

The complete device may be stamped or pressed out of any suitable material.

Some changes may be made in the construction and arrangement of my improved ash receptacle and stand without departing from the real spirit and purpose of my invention and it is my intention to cover by my claims any modified forms of structure or use of mechanical equivalents which may be reasonably included within their scope.

I claim:

1. In a device of the class described, a receptacle having an opening in its top, a trap door hinged on the under side of said top and capable of closing the said opening in said top, a spring for yieldingly holding said trap door in a closed position, a push rod extending through the top of said receptacle having one end engaging said trap door and an upwardly curved portion on said trap door for engaging said push rod when said push rod is forced downwardly for opening said trap door.

2. In a device of the class described, a receptacle having an opening in its top, a trap door hinged on the underside of said top and capable of closing the said opening in said top; said trap door having an upwardly inclined portion and located between the portion of said trap door that closes said opening and points where it is hinged to the underside of said top, a spring for yieldingly holding said trap door in a closed position, and a push rod extending through the top of said receptacle having one end capable of slidably engaging said inclined portion of said trap door.

EDWARD SCHULTZ.
